UNITED STATES PATENT OFFICE.

GRIFFITH JOHN, OF YONKERS, NEW YORK, ASSIGNOR TO OTIS ELEVATOR COMPANY, OF JERSEY CITY, NEW JERSEY, A CORPORATION OF NEW JERSEY.

SAFETY DEVICE FOR CONVEYERS.

Application filed December 22, 1917. Serial No. 208,397.

To all whom it may concern:

Be it known that I, GRIFFITH JOHN, a subject of the King of Great Britain, residing in Yonkers, in the county of Westchester 5 and State of New York, have invented a new and useful Improvement in Safety Devices for Conveyers, of which the following is a specification.

My invention relates to safeguarding apparatus for that class of conveyers used to transport passengers and freight from one point to another by means of a continuously moving support on which the load rests, such support being a series of sections connected 15 and propelled by means of a driving chain.

The object of the invention is the provision in an apparatus of the class described of automatic means to immediately halt the movement of the conveyer in the event of a 20 break in the driving chain, and so prevent any further damage to the apparatus or accident to the load which might otherwise result from a continued operation after the occurrence of such a break.

25 In the usual types of sectional continuously moving conveyers or moving stairways, the only connections between the successive sections are the links of the driving chain upon which fall the strain of drawing 30 and supporting the load in its ascent, as well as that strain due to engagement with a driving sprocket. Consequently links frequently break under their severe duty, and with a continued operation of the driving mechanism, the conveyer is in danger of becoming 35 jammed, while if the broken link is permitted to come into engagement with the driving sprocket or idler sprockets serious wreckage may result to the sprockets, driving 40 chain and other parts of the conveyer, with the added danger of an accident to the load. In my invention I meet this condition, and attain the desired object through utilizing the broken member as a circuit 45 maker in an electrical device.

Referring to the accompanying sheet of drawings. Fig. 1 is a side elevation of the essential parts of a conveyer or moving stairway in the vicinity of the driving 50 sprocket, showing my invention embodied therewith. Fig. 2 is a sectional view taken on the line $\alpha-\alpha$ in Fig. 1. Fig. 3 is a diagrammatic side elevation of a complete

driving chain for a conveyer showing the relative position of my invention therewith. 55 Fig. 4 is a wiring diagram for the control of the driving apparatus of a conveyer in connection with the present invention. Similar characters of reference indicate like parts throughout the several figures. 60

In Fig. 1, a driving chain for a conveyer is composed of links 1, each comprising two shroud plates 2, connected by cross pins 3. The links serve as connecting members between axles 4, upon which are supported 65 sections or steps 5. A driving sprocket or spur wheel 6 engages the axles 4 and cross pins 3 in well-known manner. I fix directly under and parallel to the upper or working run of the driving chain, both above and below the driving sprocket, pairs of strips of electroconductive material 7 mounted on insulating strips 8, and supported by suitable beams 9. The pairs of strips 7 are placed close under the chain in such position 75 that the broken members of any link 1 will drop thereonto, bringing the cross pins 3 into contact with both strips to complete an electric circuit across the strips through the cross pins. In the illustration, the nearer 80 shroud plate of link 1 is cut away to show the position of the cross pins in contact with the strips 7. I find it advisable to incline the end of the strips 7 to the periphery of the driving sprocket, as shown, on that side 85 to which the chain passes in its travel after engagement with the sprocket, in order that, in the event of a link breaking while on the sprocket, the same will subsequently drop onto the strips 7 without the danger of becoming caught under the latter. In the apparatus here shown, the arrangement is made for an ascending conveyer, while for a descending machine the ends of the strips 90 below the sprocket should be so inclined, or for a reversible machine the inclined feature should be added both above and below the sprocket. In Fig. 2, a cross section of a link 1 and strips 7, taken on the line $\alpha-\alpha$ in Fig. 1, shows clearly the relative position 100 of these members and makes apparent the effect of the dropping of any one of the cross pins onto the strip.

Fig. 3 shows a complete drive chain for a conveyer in its relation to the strips 7, which 105 extend throughout that part of the path of

travel of the chain in which a broken link will drop clear of the steps so that it may be used to complete an electric circuit. It will be seen that protection is afforded throughout the entire ascending or working trip of the chain, wherein breaks will invariably occur, since it is obviously unlikely that any break will take place on the return trip where the links are subjected to comparatively little strain.

In Fig. 4, I show a wiring diagram for a direct current electric motor, 10, and electromagnetically released brake, 11, for actuating the driving sprocket of a conveyer. Obviously any type of motor in connection with a suitable system of wiring might be used for the purpose. A manually closed potential switch 12 is held closed by its magnet, while a normally closed relay switch 13 controls contacts in the circuit for the magnet of the potential switch. The upper and lower sections of strips 7 are connected in parallel, and with the cross pins 3, constitute circuit closers for the magnet of switch 13. An accelerating switch 14 is connected in well-known manner across the armature of the motor 10 to automatically step out the resistance 15. To start the apparatus, the potential switch 12 is thrown in by hand, completing a circuit for its own magnet from the plus main through the magnet, conductor 16, contacts of switch 13, conductor 17 to the minus main. Circuits are simultaneously completed for the motor and brake. Now when any one of the cross pins 3 drop onto either pair of conductors 7, a circuit is completed for the magnet of switch 13 from the plus main, conductor 18, strips 7, cross pin 3, conductor 19, magnet 13, conductor 20 to the minus main. The operation of switch 13 opens its contacts and breaks the circuit previously traced for the magnet of potential switch 12, causing the latter to open, stopping the motor and applying the brake. In machines designed to be operated in either direction, the principle here outlined may be embodied in connection with suitable reversing switches.

It will be seen that the comparatively simple device herein described provides an adequate and reliable safe-guarding means to bring a conveyer to an immediate stop in the event of a break in the driving chain. Obviously those skilled in the art may make various changes in the constructions and arrangements of parts without departing from the spirit and scope of my invention.

I desire, therefore, not to be limited to the exact constructions herein described.

I claim—

1. In combination, a continuously moving conveyer, actuating apparatus therefor, and electric means comprising an open circuit adapted to be bridged to stop the actuating

apparatus, said means operable by a broken part of the conveyer, said part itself adapted to serve as a bridge for said open circuit.

2. In combination, a drive chain of a conveyer, actuating apparatus therefor, and electric means comprising an open circuit adapted to be bridged electrically to stop the actuating apparatus, said means operable by a broken part of the drive chain, the said part itself serving to constitute the bridge for said open circuit.

3. In combination, a drive chain of a conveyer, and an electrical conductor through which an electric circuit is completed by means of a contact with a broken member of the chain.

4. In combination, a drive chain of a conveyer, actuating electric motor apparatus therefor, a circuit therefor and an electrical conductor through which an electric circuit is completed to the circuit for the motor by contact with the chain to cause the actuating apparatus to stop.

5. In combination, a drive chain of a conveyer, actuating apparatus therefor, an electro-responsive device, and an electrical conductor through which an electric circuit is completed by contact with the chain to cause the actuating apparatus to stop by means of an operation of the electro-responsive device.

6. In combination, a drive chain of a conveyer, actuating apparatus therefor, an electro-conductive member adjacent to the chain to cause, through contact with the latter, as accomplished by breaking of the same a stopping of the actuating apparatus.

7. In combination, a drive chain of a conveyer, actuating apparatus therefor, an electro-conductive member extending adjacent to the chain throughout the working run of the latter to cause through contact with the chain, as accomplished by a breaking of the same, a stopping of the actuating apparatus.

8. In combination, a continuously moving conveyer, operating means therefor, a source of power supply, an electro-responsive device to connect the operating means to the source of power supply, a second electro-responsive device to control a circuit for the said electro-responsive device, an electrical conductive means operable by a broken part of in a moving part of the conveyer to close a circuit for the last named electro-responsive device, to open the first named circuit to disconnect the operating means from the source of power supply.

9. In combination with a drive chain of a conveyer, an electric motor, an electromagnetically released brake, an electro-responsive switch controlling circuits for the motor and brake, a second electro-responsive switch controlling a circuit for the said first mentioned electro-responsive switch, and an electrical conductor through which a cir-

cuit is completed by electrical contact with the chain to open the second named electro-responsive switch to cause an interruption in the circuit for the first named electro-responsive switch, to cause the same to open and to interrupt the circuits for the motor and brake.

In testimony whereof, I have signed my name to this specification in the presence of two subscribing witnesses.

GRIFFITH JOHN.
